UNITED STATES PATENT OFFICE.

LOUIS N. D. WILLIAMS, OF OGONTZ, PENNSYLVANIA.

TRANSFER OF KNITTED FABRICS.

Application filed February 23, 1923. Serial No. 620,588.

To all whom it may concern:

Be it known that I, LOUIS N. D. WILLIAMS, a citizen of the United States, residing at Ogontz, county of Montgomery, and 5 State of Pennsylvania, have invented certain new and useful Improvements in Transfer of Knitted Fabrics, of which the following is a specification, reference being had to the accompanying drawings.

10 My invention relates to the transfer of knitted fabrics as practised, for example in connection with the manufacture of hosiery, in "running on" of ribbed tops of half-hose upon the needles of machines known as 15 "footers" for the purpose of knitting the leg and foot portions of the stockings in prolongation. My invention is concerned both with a novel method of accomplishing such transfer, and with mechanism or apparatus especially adapted to the performance 20 of such method, and has for its main object, to obviate the necessity for reliance upon special skilled labor as required heretofore on account of the precise and tedious 25 manipulations involved in avoiding dropping of stitches. The latter contingency if allowed to take place, results, as is well known to those schooled in the art of stocking manufacture, in production of imperfect 30 stockings which are classed as seconds and saleable only at reduced prices. The several difficulties just pointed out I entirely overcome, and by my invention am able to effect 35 the transfer operation not only speedily, but with absolute precision to the advantage of greater economy in manufacturing. As will hereinafter appear, the process characteristic of my invention is susceptible to variation, and this is also true of the transfer 40 mechanism employed.

Other objects and attendant advantages of my invention will become readily apparent from the detailed description which follows.

45 In the drawings, Figs. I, II and III are fragmentary sectional views of a mechanism conveniently embodying my invention in one form, and showing successive steps in the transfer operation.

50 Fig. IV shows an alternative form of mechanism useful for the same purpose; and Figs. V, VI and VII are views corresponding to Figs. I, II and III of still

another modified form of transfer mechanism which may be used in carrying out 55 my improved process or method.

Referring first to the type of my invention shown in Figs. I to III inclusive it is to be observed that I employ a means, comprehensively indicated at 1, for temporarily holding the knitted fabric while the stitches are being impaled upon the needles of the knitting machine to which the fabric is to be transferred. The means 1 may take any suitable form depending upon the type of machine with which it is to be used. In the present instance, the same is shown as annular in form for use with circular knitting machines such as ordinarily employed in hosiery manufacture. Briefly described, this means consists of a ring frame 2 suitably shouldered as at 3 for the abutment of the upper or anchorage ends of the stitch holding quills or points 4. Said quills have lateral extensions 5 so that they may be securely fixed in place on the ring by a flanged annulus 6 securable in any approved manner. The lower projecting ends of the quills are slotted or fluted as at 7 so as to be capable of accommodating the hooks of the knitting needles 8 of the machine to which transfer is to be made. There is of course an individual quill provided for each needle; and the structure 1, it will be noted, is supported solely by virtue of shoulders 85 formed as the result of partial fluting of the quills as previously described. The points or quills are furthermore tapered as at 9 to facilitate, during application of the fabric, opening or dilation of the loops which I will hereinafter refer to simply as stitches and designate in the drawings by the letter α . In order that the stitches α may be properly aligned about the series of quills, the latter are provided with stop shoulders 95 indicated at 10 which cooperate in bringing about this condition. Mounting of the fabric upon the temporary holding means 1 may be accomplished manually, or said means may be employed in receiving the fabric from a knitting machine by which it is produced, and then placed upon the needles 8 of the machine for appendage of knitting of a different character from the first. The proportioning of the quills, it 100 will be noted, is such that the stitches 105

cupy a position slightly below the plane of the needle hooks after application of the holding means to the knitting machine.

For the purpose of insuring positive engagement of the needle hooks with the stitches while the latter are held in a dilated condition by the quills or points 4, I provide for subsequent relative lateral movement of the stitches and the needles. In the instance under consideration, this relation is brought about by lateral flexure of the needles, and the instrumentalities for effecting such shifting is shown as associated with the needle actuating mechanism of the knitting machine. Within each guide groove 11 of the needle cylinder 12, together with a needle 8, is placed an actuating element 13 which for convenience I will term a distending jack. This element is capable of being shifted independently of the needle and may be actuated in any convenient way, for example as by cams 14 operative upon the jack butts, and preferably disposed superjacent the cams 15 which ordinarily actuate the needles in knitting. The upper ends of the jacks are retroverted as at 16, and the turned portions normally lie within recesses 17 formed in the needle grooves. In being shifted upwardly by the cams 14, the rounded tops of the jacks 13, by cooperation with inclines 18 of the recesses 17, act after the manner of wedges to shift the upper ends of the needles laterally outward so that their hooks are thereby positioned to overlie the outer runs of the stitches α on the quills of the holding element 1. From the above it will be seen that after the stitches have been impaled upon the needles of the knitting machine to which the knitted fabric is to be applied, the needles may be laterally moved so that the stitches are positively retained within the needle hooks when the holding means 1 is bodily withdrawn, and thus incidentally stripped from the quills 4.

Referring now to the type of my invention shown in Fig. IV the relative positioning of the needles and the stitches for positive stitch retainment after the latter have been impaled upon said needles, is effected in a manner conversely to that previously described; in other words, instead of moving the needles within the dilated stitches as before I here move the stitches relative to the needles. The mechanism by which this is accomplished is entirely self-contained, and comprises an annular mounting frame 20 formed at its lower end with a projecting annular flange head 21, said head being slotted about its periphery as indicated at 22 to receive the quills 23. Said quills have laterally projecting butts 24 which prevent vertical displacement through engagement within a circumferential groove 25 or slot 25 of the head 21. The quills are

retained through aid of spring bands 26 engaging recesses 27 in the quills, and accommodated, some within the groove 25 and others in a supplemental groove 25^a. By such mounting it will be at once apparent that the quills may be rocked within the slots 22 and to this end their tops are rounded as at 28 for cooperation with a circumferential cam surface 29 of a sleeve 30 which is slidable on the frame 20, the latter being provided with a diametrical cross-bar 31 capable of being grasped in effecting its operation. The cross-bar 31 traverses slots 32 in the wall of the frame 20 which thus limit the vertical movement of the sleeve. In addition to the taper characterizing the lower end of the quills, the latter are provided with recesses or notches 33 for engaging the stitches, said notches being initially functional in a manner similar to the shoulders 10 in the first described embodiment of my invention but serving in the additional capacity of engaging the stitches so that they are compelled to follow movement of the quills. In operation, as the sleeve 30 is depressed, the quills 23 will be rocked about the corners 34 at the lower ends of their retaining slots, the springs 26 yielding to permit such motion, and the projections 24 acting at the same time to prevent vertical displacement. Such movement will result in bringing the stitches α beneath the needle hooks so that the holding device may be bodily removed as before leaving the needles stitches positively engaged in the needle hooks.

Coming now to the last modification shown in Figs. V, VI and VII, the holding means is generally similar to the type just described in that it comprises a frame 35 headed at its lower end as at 36 for retainment of the quills 37 which are in this instance held in place against movement by an insert annulus 38. It is to be especially noted that the quills are fluted or slotted throughout in this case, and that within each is guided a slide 39 having at its upper end a laterally turned butt 40 adapted to engage in a groove 41 formed in a circumferential enlargement at the lower end of a sleeve 42 which is slidable vertically upon the frame 35. Said sleeve is provided with a grasp bar 44, and is operable in a manner similar to that described of the sleeve 30 of the previous modification, movement being limited by the guide slots 45 in the frame 35. The lower ends of the slides 39 are reduced and chamfered as at 46 so as to be capable when depressed, of engaging behind the needle hooks to cause outward movement or flexure of the needles whereby the hooks are positioned to overlie the outer runs of the stitches α arrested upon the quills. The position of the parts just described is clearly shown in Fig. VI

from which it will be apparent that the temporary holding means may be bodily withdrawn vertically leaving the fabric positively engaged with the needles as shown in Fig. VII.

In conclusion, it will be seen that in each instance, the fabric stitches are maintained in an open or dilated condition by the quills of the holding means, and in this condition impaled upon the needles of the machine to which the fabric is transferred. The stitches and the needles are thereupon relatively moved so as to insure engagement of the stitches beneath the needle hooks as the temporary holding means is withdrawn. Each stitch is thereby positively engaged so that stitch dropping cannot possibly take place, thus enabling the transfer to be accomplished speedily and without requiring any special skill or dexterity on the part of the operative.

Having thus described my invention, I claim:

1. The method of transferring knitted fabrics which consists in impaling the fabric stitches upon the needles of a knitting machine, and then shifting the stitches and needles relatively to insure engagement of the stitches within the needle hooks.

2. The method of transferring knit fabrics which consists in impaling the fabric stitches, while maintained in a dilated condition, upon the needles of a knitting machine, then shifting the dilated stitches and needles relatively to insure engagement of the stitches within the needle hooks.

3. The method of transferring knit fabrics which consists in impaling the fabric stitches, while maintained in a dilated condition, upon the needles of a knitting machine, thence shifting the needles laterally within the dilated stitches to insure engagement of the stitches within the needle hooks.

4. Mechanism for transferring knitted fabrics including in combination, means for temporarily holding the fabric stitches while the latter are impaled upon the needles of a knitting machine, and means for subsequently moving the stitches and the needles relatively to engage the stitches under the needle hooks for positive retainment of the fabric when the holding means is withdrawn.

5. Mechanism for transferring knitted fabrics including in combination, means for temporarily holding the fabric stitches while the latter are impaled upon the needles of a knitting machine, and means for subsequently moving the needles laterally to position their hooks over the fabric stitches for positive retainment of the fabric when the holding means is withdrawn.

6. Mechanism for transferring tubular knitted fabrics including in combination, means for temporarily holding the fabric

stitches while the latter are impaled upon the needles of a circular knitting machine, and means for subsequently spreading the circle of needles to position the needle hooks over the fabric stitches for positive 70 retainment of the fabric when the holding means is withdrawn.

7. Mechanism for transferring knitted fabrics including in combination, means for temporarily holding the fabric stitches 75 while the latter are impaled upon the needles of a knitting machine, and means carried by the guide support for the needle for subsequently moving the needles laterally to position their hooks over the fabric stitches 80 for positive retainment of the fabric when the holding means is withdrawn.

8. Mechanism for transferring knitted fabrics including in combination, means for temporarily holding the fabric stitches 85 while the latter are impaled upon the needles of a knitting machine, and means associated with the needle actuating instrumentalities of the machine for subsequently moving the needles laterally to position their hooks over the fabric stitches for positive retainment 90 of the fabric when the holding means is withdrawn.

9. Mechanism for transferring knitted fabrics including in combination, means for temporarily holding the fabric stitches while the latter are impaled upon the needles of a knitting machine, and means operative in the guide grooves with the needles for subsequently moving the needles laterally to position their hooks over the fabric 100 stitches for positive retainment of the fabric when the holding means is withdrawn.

10. Mechanism for transferring knitted fabrics including in combination, means for temporarily holding the fabric stitches while the latter are impaled upon the needles of a knitting machine, and means individually associated with the needles for subsequently moving the needles laterally to position their hooks over the fabric stitches for positive retainment of the fabric when the holding means is withdrawn.

11. Mechanism for transferring knitted fabrics including in combination, means for temporarily holding the fabric stitches while the latter are impaled upon the needles of a knitting machine, and means individually associated with each needle and independently slideable in the needle guide grooves for subsequently moving the needles laterally to position their hooks over the fabric stitches for positive retainment of the fabric when the holding means is withdrawn.

12. Mechanism for transferring knitted fabrics including in combination, means for temporarily holding the fabric stitches while the latter are impaled upon the needles of a knitting machine, and wedge means

operative behind the needles in the guide grooves for the latter for subsequently moving the needles laterally to position their hooks over the fabric stitches for positive retention of the fabric when the holding means is withdrawn.

13. Mechanism for transferring knitted fabrics including in combination, means for temporarily holding the fabric stitches while the latter are impaled upon the needles of a knitting machine, and individual jacks mounted with the needles in the guide grooves for the latter and serving by co-operation with inclined surfaces, as wedges for subsequently moving the needles laterally to position their hooks over the fabric stitches for positive retention of the fabric when the holding means is withdrawn.

14. Mechanism for transferring knitted fabrics including in combination, means for temporarily holding the fabric stitches while the latter are impaled upon the needles of a knitting machine, individual jacks mounted with the needles in the guide grooves for the latter and serving by co-operation with inclined surfaces, as wedges

for subsequently moving the needles laterally to position their hooks over the fabric stitches for positive retention of the fabric when the holding means is withdrawn, and cams associated with the needle actuating instrumentalities for shifting the jacks independently of the needles to bring about lateral displacement of the latter as aforesaid.

15. Mechanism for transferring knitted fabrics including in combination, means for temporarily holding the fabric stitches while the latter are impaled upon the needles of a knitting machine, and means for subsequently flexing the needles to position their hooks over the fabric stitches for positive retention of the fabric when the holding means is withdrawn.

In testimony whereof, I have hereunto signed my name at Philadelphia, Pennsylvania, this 14th day of February, 1923.

LOUIS N. D. WILLIAMS.
